UNITED STATES PATENT OFFICE.

CHARLES B. JACKSON, OF DENVER, COLORADO, ASSIGNOR, BY MESNE ASSIGNMENTS, TO THE PATENT HOLDING COMPANY, OF DENVER, COLORADO.

NON-REFILLABLE BOTTLE.

No. 833,134.

Specification of Letters Patent.

Patented Oct. 9, 1906.

Application filed October 14, 1905. Serial No. 282,713.

To all whom it may concern:

Be it known that I, CHARLES B. JACKSON, a citizen of the United States, residing in the city and county of Denver and State of Colorado, have invented certain new and useful Improvements in Non-Refillable Bottles; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in non-refillable bottles, my object being to provide a thoroughly practicable construction adapted to prevent fraud by the refilling of bottles that have once been used with goods 20 inferior to the original contents.

25 My further object is to provide a device of this class which shall be exceedingly simple in construction and the cost of which shall be only slightly greater than that of the ordinary bottle.

30 My improved construction will be thoroughly understood by reference to the accompanying drawings, in which is illustrated an embodiment of the invention.

35 In the drawings, Figure 1 is a vertical section of a bottle constructed in accordance with my improvement and equipped with the devices which make it impracticable to refill the same after its original contents have been 40 discharged. In this figure the bottle is shown in the upright position with the plunger valve seated. Fig. 2 shows the bottle inverted, the direction of the flow of the escaping liquid being indicated by the arrows. In

45 this view the plunger-valve is unseated. Fig. 3 is a cross-section taken through the bottle-neck and plunger-valve. This section is taken on the line 3 3, Fig. 1. Fig. 4 is a detail view of the cap applied to the outer extremity of the bottle-neck. Fig. 5 is a detail view of the plunger-valve. Fig. 6 is a fragmentary sectional view of the upper part of the bottle shown in detail or without the devices rendering the bottle non-refillable. 50 Fig. 7 is a sectional view of a bottle, showing another form of my improved construction. Fig. 8 is a view of the same, but with the bottle inverted to show the position of the valve-

plunger during the escape of the liquid from the bottle.

55

The same reference characters indicate the same parts in all the views.

Let the numeral 5 designate the body of the bottle, and 6 the neck thereof. The base of the neck is provided with the interiorly-projecting shoulder or ledge 7, upon which rests a seat 8, preferably composed of cork. Located within the bottle-neck and adapted to engage this seat is a plunger-valve 9, which, as shown in the drawings, has a conical extremity 10, adapted to engage a counterpart opening formed in the seat 8 when the bottle is in the upright position or that shown in Fig. 1. This plunger - valve 9 is provided with a body part extending beyond the valve part proper, 10, thus giving the device 9 sufficient weight to facilitate the removal of the liquid from the bottle-neck when the bottle is in use. This device 9, as shown in the drawings, is provided with longitudinal 70 grooves 9^a to permit the liquid to flow freely between the body of the plunger and the neck of the bottle when it is desired to remove the liquid therefrom.

75 In order to further facilitate the removal of the liquid and also in order to prevent excessive friction between the plunger and the neck of the bottle, the plunger is provided with a number of pins or projections 9^c, which engage the interior surface of the bottle-neck, 80 thus greatly reducing the friction and at the same time permitting the necessary space to allow the liquid to flow freely around the plunger when the bottle is tipped to the proper position.

90 The extremity of the plunger remote from the valve part 10 is provided with a recess 12. The plunger is also provided at its recessed end with lateral grooves 9^d, which register with the longitudinal grooves 9^a, allowing the 95 liquid to pass freely from the space surrounding the plunger into the recess 12 when the plunger is in the position shown in Fig. 2 or when the bottle is inverted for the purpose of removing the liquid.

100 Attention is called to the fact that it is not necessary to completely invert the bottle, as shown in Fig. 2, in order to remove the liquid. The vertical inverted position is shown for convenience of illustration only.

105 To the outer extremity of the bottle-neck

is applied a cap 13, having a circumferential groove 14, adapted to receive the upper extremity 6^a of the bottle-neck above a ledge or shoulder 6^c. The part of the cap 15 outside of the groove engages the ledge 6^c of the neck, while the part 16 of the cap enters the bottle-neck. This part 16 is provided with an interior projection 17, adapted to enter the recess 12 of the plunger-valve when the latter is in the position shown in Fig. 2. This cap has a small longitudinal opening 18 for the escape of the liquid when the bottle is in use. This opening may be closed by a small stopper 19 in order to seal hermetically the contents of the bottle.

The cap 13 is cemented to the bottle-neck, whereby it becomes virtually an integral part thereof, making it impossible to remove the cap without breaking the neck. Hence it becomes impossible to refill the bottle without destroying the latter or mutilating it in such a manner as to render it valueless.

From the foregoing description the use of my improved device will be readily understood.

While filling the bottle with its original contents the bottle-neck is open, as shown in Fig. 6. As soon as the bottle has been filled the cork seat 8 is inserted and caused to engage the ledge 7. The plunger-valve 9 is then dropped into place, after which the cap is applied in the manner heretofore stated.

The plunger-valve and cap 13 are preferably composed of glass. The small stopper 19 may also be of glass or cork.

Attention is called to the fact that in my improved construction it is not necessary to use any metal parts, only glass and cork being required. This is an important feature, since metal parts are extremely objectionable owing to the fact that the liquid contents of the bottle are injured by coming in contact with the metal. The metal parts are usually corroded with the contents of the bottle, thus prohibiting the use of metallic features in a bottle of this class.

When it is desired to remove a portion of the contents of the bottle, the small plug 19 is removed from the cap, when the bottle may be tipped or tilted sufficiently to allow the plunger-valve to unseat, or assume the position shown in Fig. 2. The contents of the bottle may then be readily removed, the liquid flowing as indicated by the arrows in Fig. 2.

When it is desired to eject the liquid in intermittent jets, the bottle is moved back and forth and suddenly stopped, thus causing the plunger-valve to reciprocate within the neck. Every time this valve moves forwardly it forcibly ejects the liquid between it and the cap through the longitudinal opening 18 of the latter.

Assuming that the bottle is inverted, or in the position shown in Fig. 2, if it is attempted

to refill the same by pressure the air and liquid entering the passage 18 will act upon the plunger-valve to seat the same before any liquid can be forced into the bottle. It is thus believed that it is practically an impossibility to reuse the bottle after its original contents have been discharged.

The cap 15 of the bottle is preferably provided with a cork washer A, forming a sort of cushion which the plunger engages when at its outward limit of movement in the bottle-neck, thus preventing the possible breakage of the plunger by striking against the glass cap.

In the form of construction shown in Figs. 7 and 8 I will designate the valve-seat as 10^a and the plunger-valve as 9^e, since these parts differ somewhat in construction from those shown in the other views. The valve-seat 10^a is preferably composed of cork, and its upper part is conical to enter a recess 12^a, formed in the adjacent extremity of the plunger-valve. The opposite extremity of the plunger-valve is also provided with a recess 12^c, adapted to receive the short neck portion 17 of the cap 18. As this form of the device performs substantially the same function as the other form of mechanism and operates in substantially the same way it need not be further described in detail.

Attention is called to the fact that by virtue of the recess 12 or 12^c in the outer extremity of the plunger a quantity of liquid is always held by the plunger, and this liquid is discharged through the orifice of the cap during the first outward movement of the plunger during the process of emptying the bottle or discharging liquid therefrom. It is evident that after using a portion of the contents of the bottle and returning the latter to the upright position the recess in the outer extremity of the plunger will remain filled with liquid. This is an important feature in actual practice. My plunger-valve is a novel feature and serves not only to prevent the refilling of the bottle after it has been once emptied, but it also aids in emptying the bottle, since it has a limited reciprocating movement within the bottle-neck, which aids in ejecting the liquid. The discharge of the bottle's contents is further accelerated by reason of the liquid-filled recess in the outer extremity of the plunger, whereby a small quantity of liquid is always in position to be immediately forced through the orificed cap during the first outward movement of the unseated plunger-valve.

Having thus described my invention, what I claim is—

1. In a non-refillable bottle, the combination of a bottle having a ledge in the neck, a valve-seat applied to the ledge, a plunger-valve having one extremity fashioned to engage said seat, the valve having a body part extending beyond its valve extremity and

giving the device sufficient weight to cause it to seat and unseat quickly according to circumstances, the plunger-valve being fashioned exteriorly to allow the liquid contents 5 of the bottle to flow around the valve when the latter is unseated, and a cap having a central perforation to allow the escape of the liquid, the said perforation being open at its inner extremity, the bottle-neck being un- 10 obstructed between the outer extremity of the plunger and the cap to allow the plunger-valve to engage the cap when the valve is unseated, the outer extremity of the valve having a recess in line with the perforation of 15 the cap, the recess being in communication with the space between the valve and the bottle-neck when the outer extremity of the plunger engages the cap.

2. A bottle of the class described, provided 20 with a valve-seat at the base of the neck, a plunger-valve located in the neck and adapted to engage the seat, the said valve having a body part projecting beyond its seating extremity, the body part of the valve being exteriorly fashioned to allow the liquid to flow therearound, the outer extremity of the bottle-neck being provided with a cap secured in place thereon and having a central longitudinal opening for the escape of the liquid 25 contents of the bottle when the valve is unseated, the outer extremity of the plunger-valve having a cavity in line with the opening in the cap, and having also a lateral recess forming a communication between the 30 said cavity and the space between the plunger-valve and the bottle-neck, the inner extremity of the cap-opening communicating freely with the cavity of the valve.

3. A bottle of the class described, provided 40 with a valve-seat, a plunger-valve having one extremity fashioned to engage said seat and having a body part projecting beyond the valve extremity, the extremity of the plunger remote from the valve extremity having 45 a recess, the body of the device being exteriorly fashioned to allow the liquid to pass around the same, and its outer edge being grooved to allow the liquid to enter the said recess, and a cap applied to the neck of the 50 bottle and forming a stop to limit the outward movement of the plunger-valve, the said cap being provided with a central projection adapted to enter the recess of the plunger-valve, the cap being also provided 55 with a central longitudinal opening for the purpose set forth.

4. A non-refillable bottle comprising the bottle proper having a ledge, a valve-seat applied to the ledge and having a conical opening, a plunger-valve having a cone-shaped valve extremity adapted to enter the opening of the valve-seat, the body of the device beyond the valve part being exteriorly shaped to allow the liquid to flow around the 65 valve when the bottle is held in the proper

position, the device being provided at its extremity remote from the valve part with a cavity, the plunger-valve being exteriorly fashioned to allow the liquid to flow there- 70 around and enter said cavity when the bottle is tipped to the position to allow its contents to escape, the outer extremity of the bottle-neck having a cap provided with a central perforation in line with the cavity of the valve, the inner extremity of the perforation having free communication with the cavity of the valve when the valve engages the cap, the bottle-neck being unobstructed between the valve and the cap. 75

5. A non-refillable bottle comprising the 80 body of the bottle having a neck, a valve-seat applied to the base of the bottle-neck, a plunger-valve having a cone-shaped valve extremity adapted to engage the valve-seat, the said device having a body part extending 85 beyond the valve part, the body part having exterior projections adapted to engage the inner surface of the bottle-neck and facilitate the passage of the liquid around the plunger-valve when the bottle is tipped to a 90 suitable position, the plunger-valve having a cavity in its outer extremity, the outer extremity of the bottle-neck having a cap provided with a central longitudinal opening in line with the cavity of the valve, the inner 95 extremity of the cap-opening having free communication with the cavity of the valve when the latter is unseated and in engagement with the cap, the neck of the bottle being unobstructed between the valve and the 100 cap.

6. In a bottle of the class described, the combination with the bottle-neck, of a cap having a circumferential groove adapted to receive the outer extremity of the bottle-neck, the said cap being cemented in place, and provided with an opening for the escape of the contents of the bottle, and a plunger-valve located in the bottle-neck, the latter being provided with a suitable seat for the 105 valve, the plunger-valve having a cavity in its outer extremity in line with the opening through the cap, the inner extremity of the cap-opening having free communication with the cavity of the valve when the latter is unseated and in engagement with the cap, the bottle-neck being unobstructed between the 110 plunger-valve and the cap. 115

7. In a non-refillable bottle, the combination with the bottle-neck, of a valve-plunger 120 located therein, a seat for the valve, one of the said devices having a cone-shaped part adapted to enter an opening formed in the other part, and a cap for the bottle-neck, the said cap being provided with a closable ori- 125 fice, the plunger having a longitudinal movement in the bottle-neck, the cap forming a stop to limit its outward movement while the valve-seat limits its inward movement, the plunger-valve having a cavity in its outer 130

extremity, the said cavity being in free communication with the inner extremity of the cap-orifice, when the outer extremity of the plunger is in engagement with the cap, the bottle-neck being unobstructed between the plunger and the cap.

8. In a non-refillable bottle, the combination with the bottle-neck, of a valve-seat therein, a plunger-valve adapted to have a longitudinal movement in the neck of the bottle, a cap limiting the outward movement of the said valve, and a cushion-washer applied to the cap and adapted to be engaged by the valve when at its outward limit of movement, the said cap having a central longitudinal escape-orifice, the outer extremity of the plunger being provided with a cavity in free communication with the inner extremity of the cap-orifice when the outer extremity of the valve is in engagement with the cap, the bottle-neck being unobstructed between the valve and the cap.
9. In a non-refillable bottle, the combination with the bottle-neck, a valve-seat, a valve-plunger and a cap, the plunger having a limited longitudinal movement in the neck of the bottle between the cap and the valve-seat, the inner extremity of the cap having a short neck and the adjacent extremity of the plunger-valve having a recess adapted to receive the neck of the cap, the cap having a closable orifice communicating with the re-

cess of the valve, the latter being provided around its recess with lateral apertures for the purpose set forth.

10. In a non-refillable bottle, the combination of the bottle-neck, a valve-seat, a valve-plunger, and a cap, the plunger having a limited longitudinal movement in the neck of the bottle between the cap and the valve-seat, the inner extremity of the cap having a short neck, and the adjacent extremity of the plunger-valve having a recess adapted to receive the neck of the cap, the cap having a closable orifice communicating with the recess of the valve.

11. In a non-refillable bottle, the combination with the bottle-neck, of a plunger located therein, the outer extremity of the plunger having a central cavity, and a cap for the bottle-neck, the said cap being provided with a closable orifice in line with the cavity of the plunger and having its inner extremity in free communication with the said cavity when the plunger engages the cap, the bottle-neck being unobstructed between the plunger and the cap.

In testimony whereof I affix my signature in presence of two witnesses.

CHARLES B. JACKSON.
